COMBINED KNIFE AND KEY HOLDER

Wallace A. Monson, St. Paul, Minn., assignor to
Brown & Bigelow, St. Paul, Minn.

Application August 14, 1957, Serial No. 47,364

Term of patent 14 years
(Cl. D87—3)

Fig. 1

Fig. 2

Fig. 3

Fig. 4

Fig. 5

Figure 1 is a perspective view of a combined knife and key holder, showing my new design;

Figure 2 is a top plan view thereof;

Figure 3 is a top plan view thereof, showing one key hook in detached position;

Figure 4 is a side elevation thereof; and

Figure 5 is an end elevation thereof.

The opposite side of the combined knife and key holder is plain and unornamented.

I claim:

The ornamental design for a combined knife and key holder, as shown and described.
